CONTROL APPARATUS

Mirl E. Whitenack, Chicago, Ill., assignor to Hurley Electronic Controls, Inc., Chicago, Ill., a corporation of Illinois

Application May 27, 1942, Serial No. 444,740

8 Claims. (Cl. 200—56)

This invention relates to control apparatus, and has for its principal object to provide an improved control apparatus of the character in which a Bourdon tube or equivalent pressure-sensitive device is provided with a contact element mounted adjacent the free movable end thereof.

Various forms of apparatus in which a Bourdon tube actuates a contact element have been proposed heretofore. Apparatus of this character heretofore proposed has not been of such design as to be capable of meeting the exacting requirements of modern sensitive electrical control circuits. The apparatus provided by the present invention is of such design and construction as to be extremely accurate in its operation (within the limits of the Bourdon tube itself), and so provides an actuating mechanism for use in conjunction with modern electronic control circuits which possesses sensitivity commensurate with that of the control circuit.

Control apparatus according to the invention comprises a Bourdon tube having a contact element mounted thereon adjacent the closed movable end thereof, and advantageously in insulated relationship therewith. A second adjustable contact element cooperates with the first contact element. Means for adjusting the position of the second contact element comprise a carriage on which said contact element is mounted, and ways in which said carriage may slide substantially along the path of travel of the contact element mounted adjacent the end of the Bourdon tube. In addition, means are provided for sliding the carriage and the contact element thereon in the supporting ways to adjust the second contact element to a chosen position in the normal path of travel of the first-mentioned contact element. The substantially straight-line movement of the carriage carrying the adjustable contact element closely follows the path of travel of the contact element mounted adjacent the end of the Bourdon tube.

One of the contact elements (advantageously the one mounted on the Bourdon tube) preferably is formed with a contact surface which in cross-section taken substantially in the place of movement of the Bourdon tube is curved convexly toward the other contact element. The other contact element preferably is substantially flat in a plane substantially tangential to the curved contact element. This configuration of the contact elements insures that when the carriage is moved to follow the movement of the Bourdon tube, such movement of the two parts will be substantially proportional along substantially the full length of their paths of travel.

Preferably the apparatus also includes means for giving visual indication of the position of the carriage and the contact element thereon. Such

means comprise a pointer, and means connecting the pointer to the carriage in such manner as to move the pointer proportionally to movement of the carriage. To this end, a pointer may be pivotally mounted for movement through an angle at least approaching 360° to traverse an appropriate scale. A pinion connected to said pointer adjacent its axis of pivot engages with rack means. Linkage means connects the rack means to the carriage in such manner as to move the rack and thereby to move the pointer proportionally to movement of the carriage.

The invention is described in greater detail below with particular reference to the accompanying drawing, in which

Fig. 1 is a plan of apparatus constructed in accordance with the invention; and

Fig. 2 is an end view of the carriage assembly.

The apparatus shown in the drawing comprises 20 a Bourdon tube 10 mounted by conventional mounting means 11 in a case 12. A suitable opening 13 is provided to admit a fluid under pressure to the open end of the Bourdon tube. At the closed end of this tube, there is mounted a 25 contact element 14. The contact element 14 preferably is secured to and electrically insulated from the closed end of the Bourdon tube by an insulating block 15.

An adjustable contact element 16 cooperates 30 with the contact element 14. The adjustable contact element 16 is securely mounted by a screw 17 on a carriage 18. The carriage is formed with grooves 19 (Fig. 2) for engagement with ways 20. The ways 20 are secured by screws or other means 35 to the back of the case 12. The ways 20 are mounted in such position as to be substantially parallel to the normal path of travel of the contact element 14. Consequently, the carriage 18, in sliding in the ways 20, carries the contact element 16 in a straight line along substantially the same path that is followed by the contact element 14, whereby these two contact elements are always in cooperating relation regardless of the adjusted position of the carriage.

It will be noted that the contacting surface of the contact element 14 is of such configuration that, in a cross section taken substantially in the plane of movement of the free end of the Bourdon tube, it is curved convexly toward the contact element 16. Such curvature may be secured by making the contacting portion of the element 14 spherical, hemispherical, cylindrical, semi-cylindrical, or of other appropriate shape. The contact element 16 mounted on the carriage is substantially flat in a plane substantially tangential to the curved surface of the contact element 14. In consequence of this configuration of the contact elements, any movement of the carriage following the path of movement of the contact ele-

ment 14 is at all contact positions substantially proportional in extent to the extent of movement of the contact 14, regardless of any tilting of the contact 14 as it moves in its path of travel.

To move the carriage 18 in the ways 20, a shaft 21 is provided. This shaft is threaded over at least a part of its length, and the threaded portion enters into threaded engagement with a correspondingly threaded element 22 secured to the carriage. The free end of the shaft 21 may be journaled in a bearing 23 at the end of the carriage to prevent even slight wobbling of the shaft. The shaft 21 extends outside the case 12, through a bearing 24 provided in suitable supporting block 25. A knob 26 secured to the end of the shaft outside the case is provided for turning the shaft.

In order to prevent axial movement of the shaft 21, a collar 27 is secured thereto and bears against the end of the bearing 24 or other suitable stationary member. A spring 28 is mounted in a recess in the block 25. This spring, which is held under compression by a plate 29 secured to the block 25, presses the collar 27 against the end of the bearing 24, and so prevents axial movement, without allowing backlash, of the shaft 21.

By turning the knob 26, the carriage is caused to slide in its ways, thereby carrying the contact element 16 to a chosen position with respect to the contact element 14. In order to secure a fine setting of the carriage 18 and the contact element 16 carried thereby, the threads on the shaft 26 may be fine, accurately cut micrometer threads.

For the purpose of securing a visual indication of the setting of the carriage 18, a pointer 30 is provided. The pointer 30 is pivotally mounted by means of a shaft 31 approximately in the center of the case 12, and is arranged to traverse a scale 32 which advantageously extends almost completely around the periphery of the case 12. The pivotal mounting of the pointer 30 advantageously is such as to permit movement through at least substantially 360° so that the pointer may fully traverse the scale.

A pinion 33 is mounted on the shaft 31 which carries the pointer 30. A rack 34 at the end of an arm 35 engages the pinion 33. The arm 35 is pivoted on a pin 36, so that rocking of the arm about this pin will move the rack in such manner as to rotate the pointer about its pivot 31. The curved end 37 of the arm 35 is connected by a link 38 to the carriage 18, and is positioned above the adjustable contact element 16 as indicated by the dotted line across the tip of end 37 in Fig. 1. The link 38 is pivotally secured at one end to the end 37 of the rack arm, and is pivotally secured at its other end to the carriage. The pivot pins at each end of the link 38 may be adjustably secured in grooves or slots 39 and 40 in the arm 37 and the carriage 18, respectively, so as to permit adjustment of the position of the pointer relatively to the position of the carriage in initially setting or in calibrating the apparatus.

When the carriage is caused to slide in its ways, the rack 34 is moved by the link 38 to turn the pinion 33 and so to cause the pointer to traverse the scale. The scale may be graduated in whatever units (of pressure, temperature or the like) suit the use to which the apparatus is to be put. The magnitude in number of units of the scale graduations depends of course on the stiffness of the Bourdon tube, which determines the magni-

tude of the forces in connection with which it is designed to be used.

In setting or calibrating the above-described apparatus, the pointer is set to read zero (or other basic reference value) by suitable adjustment of the link 38 when the pressure in the Bourdon tube 10 corresponds to such basic reference value and the carriage is in such position that the contacts 14 and 16 are then barely touching. The scale is graduated in appropriate units corresponding to each unit increase (or decrease) of the pressure in the Bourdon tube. This graduation is advantageously carried substantially around the full 360° through which the pointer 30 may swing. Obviously the graduations may be carried to an extent greater or less than 360°. At all points on the scale, however, the number of units indicated by the pointer corresponds to the position of the carriage when the contacts 14 and 16 are just barely touching with the pressure in the Bourdon tube corresponding to the indicated number of units.

In use, the contact elements 14 and 16 are connected to suitable electrical apparatus for controlling flow, pressure, temperature or other factor to be controlled. For example, the contact elements may be suitably connected into an electronic control circuit such as is described in United States patent to Mirl E. Whitenack, No. 2,208,235, dated July 16, 1940. The Bourdon tube may be connected to a vessel containing a fluid under pressure (or under vacuum), and the apparatus then may be used in controlling the pressure of the fluid; or it may be connected to a fluid subjected to varying pressures corresponding to varying rates of flow of a fluid through a conduit, in which case the apparatus may be used in controlling the rate of flow of such fluid; or the Bourdon tube may be filled with a thermally expansible fluid and may then be used in controlling the temperature of a body to which the thermally expansible fluid is exposed. Various other uses of the new apparatus will be apparent to those skilled in the art.

The new control apparatus is of such design that it may be constructed to function with extreme accuracy (within the limits of accuracy of the Bourdon tube itself). The arrangement of the carriage 18, sliding in the ways 20, along a substantially straight-line path, is such that the contact element carried by the carriage closely follows the normal path of travel of the contact element carried by the Bourdon tube. The curvature of the contacting surface of the contact element at the end of the Bourdon tube allows for angular movement of this contact during movement of the Bourdon tube without altering the effectiveness with which it makes contact with the cooperating contact element, and without necessitating variation in the size of the unit graduations on the scale. At the same time the disadvantages of a point contact element are eliminated. The manner in which the carriage is mounted, and the spring means preventing backlash of the carriage operating shaft, enables the carriage to be set with the extreme accuracy required in modern control instruments. The arrangement by which the pointer is connected to the carriage to give a full 360° scale reading possesses obvious advantages in enabling the scale to be made large and easily read, and to permit of correspondingly fine adjustments in the setting of the carriage 18.

I claim:

1. Control apparatus of the character described

comprising a Bourdon tube, a first contact element mounted thereon adjacent the closed movable end thereof whereby said contact element moves in a path similar to that of the moving end of said Bourdon tube, a second contact element cooperating with said first contact element, means for adjusting the position of said second contact element comprising a carriage on which said second contact element is mounted, ways in which said carriage may slide, said ways being positioned substantially parallel to said path of movement of the first-mentioned contact element, means for sliding said carriage and the contact element thereon in said ways to adjust said second contact element to a chosen position in said path of movement of the first-mentioned contact element, and means including the configuration of said contact elements for maintaining the same proportional extent of movement of both of said contact elements at all contact positions of said elements along said path of movement.

2. Control apparatus of the character described comprising a Bourdon tube, a contact element mounted thereon adjacent the closed movable end thereof, a second contact element cooperating therewith, means for adjusting the position of said second contact element comprising a carriage on which said second contact element is mounted, ways in which said carriage may slide substantially along the path of travel of the first-mentioned contact element, and means for sliding said carriage and the contact element thereon in said ways to adjust said second contact element to a chosen position in the normal path of travel of the first-mentioned contact, and means for giving visual indication of the position of said carriage comprising a pointer, and means connecting said pointer to said carriage in such manner as to move the pointer proportionally to movement of the carriage.

3. Control apparatus of the character described comprising a Bourdon tube, a contact element mounted thereon adjacent the closed movable end thereof in insulated relation therewith, a second contact element cooperating therewith, means for adjusting the position of said second contact element comprising a carriage on which said second contact element is mounted, ways in which said carriage may slide substantially along the path of travel of the first-mentioned contact element, and means for sliding said carriage and the contact element thereon in said ways to adjust said second contact element to a chosen position in the normal path of travel of the first-mentioned contact, and means for giving visual indication of the position of said carriage comprising a pointer pivotally mounted for movement through an angle at least approaching 360°, a pinion connected to said pointer adjacent its axis of pivot, rack means engaging said pinion, and a linkage connecting said rack to the carriage in such manner as to move the rack and thereby to move the pointer proportionally to movement of the carriage.

4. Control apparatus of the character described comprising a Bourdon tube, a contact element mounted thereon adjacent the closed movable end thereof, a second contact element cooperating therewith, and means for adjusting the position of said second contact element comprising a carriage on which said second contact element is mounted and movable substantially in the normal path of travel of the first-mentioned contact element, one of said contact elements

having a contact surface which in cross-section taken substantially in the plane of movement of the Bourdon tube is curved convexly toward the other contact element, and the other of said contact elements having a contact surface which is substantially flat in a plane substantially tangential to the curved contact element.

5. In control apparatus comprising a Bourdon tube having a contact element mounted thereon adjacent the closed movable end thereof and an adjustable contact element cooperating therewith, the improvement which comprises forming one of said contact elements with a curved contacting surface which in cross section taken substantially in the plane of movement of the Bourdon tube is curved convexly toward the other contact element, and forming the other of said contact elements with a contacting surface which is substantially flat in a plane substantially tangential to the curved contact element.

6. In control apparatus comprising a Bourdon tube having a contact element mounted thereon adjacent the closed movable end thereof and an adjustable contact element cooperating therewith, means for supporting and adjusting the position of said adjustable contact element comprising ways arranged substantially parallel to the normal path of travel of the contact element mounted adjacent the closed end of the Bourdon tube, a carriage mounted in said ways and adapted to slide therein, means for mounting the adjustable contact element on said carriage, a shaft extending into threaded engagement with the carriage, and means preventing axial movement of said shaft, whereby rotation of said shaft imparts motion to the carriage in its supporting ways.

7. In control apparatus comprising a Bourdon tube having a contact element mounted thereon adjacent the closed movable end thereof and an adjustable contact element cooperating therewith, means for supporting and adjusting the position of said adjustable contact element comprising ways arranged substantially parallel to the normal path of travel of the contact element mounted adjacent the closed end of the Bourdon tube, a carriage mounted in said ways and adapted to slide therein, means for mounting the adjustable contact element on said carriage, a shaft extending into threaded engagement with the carriage, a collar on said shaft, a fixed bearing for engagement with said collar, and spring means pressing the collar against said fixed bearing to hold the shaft without backlash against axial movement, whereby rotation of said shaft imparts motion to the carriage in its supporting ways.

8. In control apparatus, the combination with a Bourdon tube having a moving contact mounted thereon adjacent the closed movable end thereof so as to follow a path similar to that of the moving end of said tube, and an adjustable contact cooperating with said moving contact and normally stationary with respect thereto, of means for adjusting said adjustable contact to move with respect to said moving contact substantially along said path followed by said moving contact, and means including a convex contact surface on one of said contacts and a substantially planar contact surface on the other of said contacts for maintaining a tangential relation between said contact surfaces at all contact positions of said contacts along said path.

MIRL E. WHITENACK.
